PROJECTILE.

Application filed February 10, 1923, Serial No. 618,339. Renewed April 2, 1927.

This invention relates to projectiles, and particularly to projectiles of the armor-piercing type.

Armor-piercing projectiles heretofore employed have been furnished with base-plugs formed from a solid block of steel of massive proportions, which plugs have been securely screwed into the rear of the projectile body. The main purpose of this form of plug has been to constrain gases generated by the explosion of a charge of explosives contained within a cavity in the projectile in such a manner that the walls of the projectile are subjected to the full expansive force of the explosive gases and are thereby disrupted into numerous fragments. The effect sought is technically known as "complete fragmentation".

The above type of base-plug gave satisfactory results for many years, but as a result of the increase in the range of modern gun fire a projectile is required to effect perforation of armor under new conditions. The line of fire at long ranges is not perpendicular or normal to the face of vertical armor, but is considerably inclined thereto. This change in the direction at which the projectile encounters the armor has caused the projectile to be subjected to powerful side stresses, as well as increased longitudinal stresses, resulting in failure of the projectiles to penetrate and their destruction on the face of the armor.

In order to increase the ability of projectiles to withstand side stresses and to secure what is technically known as "penetration at oblique impact", it has heretofore been proposed to chamfer or taper the projectile body from the vicinity of the rotating band rearwardly to the base, thread this conical portion, and attach thereto a band of metal, cylindrical on the outside diameter and tapered inside, to fit the conical portion of the projectile body. When a projectile thus constructed strikes its objective obliquely, the interiorly tapered band is torn loose, thereby permitting the reduced portion of the projectile to enter the hole in the plate more readily. This construction, while partially accomplishing its purpose, is expensive, limited in application, and weakens the projectile at the base which is detrimental to "complete fragmentation".

An object of this invention is to provide a

projectile of simple and practical construction which is capable of withstanding side stresses encountered when penetrating at oblique impact. Other objects will appear more fully hereinafter.

Broadly stated, the invention comprises an armor-piercing projectile, having an explosive chamber therein, provided with a flexible closure at the rear end thereof for the double purpose of increasing the ability of the projectile to pierce armor, when striking at oblique angles, and, of maintaining tightness of the explosive chamber notwithstanding deformation of the rear portion of the projectile body, thus preserving the fragmenting qualities of the projectile.

The invention will be readily understood by reference to the accompanying drawings, illustrating several embodiments of the inventive idea, in which—

Fig. 1 is a longitudinal sectional view of a projectile embodying the present invention;

Fig. 2 is a detail sectional view of one form of base-plug which may be employed in my improved projectile;

Fig. 3 is a similar view of another form of base-plug which may be employed;

Fig. 4 is a diagrammatic view illustrating the conditions which exist when a projectile strikes armor plate at angles less than 45° from the normal;

Fig. 5 is a diagrammatic view illustrating the action of a projectile when striking at angles greater than 60° from the normal; and

Fig. 6 is a similar view illustrating one of the various conditions which exists when the projectile strikes at an angle between approximately 45° and 60° from the normal.

Referring to the drawings, wherein like reference numerals indicate like parts throughout the several views, 7 is the body portion of my improved projectile having secured to the forward end thereof an armor-piercing cap 8 and windshield 9 of any suitable construction. Formed interiorly of body 7 in any suitable manner is the usual cavity or chamber 10 for carrying the bursting charge of explosives.

After the explosive charge is placed in cavity 10, it is necessary to seal the rear end of the cavity, and in order that this seal may be preserved, to maintain the fragmenting qualities of the projectile even when striking armor at oblique angles, it is necessary that

the base-plug, closing the rear end of cavity 10, so cooperate with the walls of the shell as to overcome the tendency of the rear end of the shell to be crushed, sheared, or otherwise disrupted, owing to the lateral strains developed at the rear of the shell. To this end the base-plug 11, in conformity with this invention, is so constructed as to be flexible, and is secured to body 7 in any suitable manner as by means of screw-threads 12.

Instead of being flat or slightly concave, as in the usual construction, the inner face 13 of base-plug 11 is convex, and of a truncated conical shape projecting slightly into explosive chamber 10. At the forward end of face 13, and formed concentrically therewith, is a threaded opening 14 for receiving a fuse or exploder 15 of any suitable type. Fuse-opening 14 is widened at the rear to form an axial cavity 16. It will be understood that, while cavity 16 is shown as conical in shape, throughout a portion of its length, the same may be of any desired contour, its purpose being to remove material around the axis of plug 11 sufficient to render the plug elastic and yielding to side stresses which deform, or tend to deform, the projectile when penetrating armor plate at oblique angles. As illustrated in Fig. 1, the rear end of cavity 16 may be open. Preferably, however, said cavity is closed as shown in Fig. 2 by a detachable plate 17 held in place by means of screws 18. If desired, a gasket 19 may be fitted between plate 17 and plug 11 to prevent gases from entering cavity 16 when the projectile is fired from the gun. A gasket 20 is usually provided between the plug 11 and body 7.

Cavity 16 may be filled with some yielding material such as sand or aluminum which, by its opposition to deformation of the plug, will assist in maintaining a gas-tight connection between said plug and the body 7. As shown in Fig. 3, a yielding material 21, such as aluminum, is employed for filling cavity 16 and is held in place in any suitable way, as by calking the edge of the material into an undercut groove 22 formed in plug 11 adjacent the rear end thereof. When the rear end of the body 7 is subjected to the side stresses of penetration, the aluminum will be extruded from cavity 16.

Preferably, the inner face 13 of plug 11 is hollowed out near the periphery to form an annular groove 23 and lip 24 which will act as an obturator.

The operation of my improved projectile is as follows:—

Referring first to Fig. 4, illustrating the conditions which exist when the projectile strikes side armor at an angle less than 45° from the normal, in this instance the point of the projectile crashes through cap 8 and windshield 9 and penetrates immediately into the face of the armor as shown in Fig. 4a.

The section of the plate opposite the nose of the projectile is not symmetrical with the line of fire and its reaction is inclined to said line of fire, resulting in a transverse movement which tends to bring the axis of the projectile perpendicular to the face of the plate. These conditions are further illustrated in Fig. 4b, which also illustrates the principal force acting. This effect is known as "side-whip" of the projectile. Its force tends to bend the projectile around the rim of the hole being punched in the armor plate. The projectile body yields elastically under the forces acting and continues to penetrate until the base portion, containing the base-plug, attempts to enter the punched hole. When the base-plug is formed of a solid block of steel, it is practically unyielding and, at this point, produces destructive cross-breaking stresses which frequently break the rear end of the projectile or greatly weaken the same. When my improved flexible base-plug is used, however, the plug yields in the same manner as the projectile body, absorbs some of the forces acting on the rear end of the projectile and thereby assists in holding the projectile intact and in accomplishing perforation of the plate.

When the projectile strikes at more than 60° from the normal, this usually being the case where the projectile encounters horizontal or deck armor, the result is as indicated in Fig. 5. The projectile strikes the plate with the side of its ogive and does not penetrate immediately but bends the armor inwardly. This action, as in the previous case, tends to retard the motion of the forward part of the projectile, thereby causing a transverse movement of the longitudinal axis. This movement is, however, away rather than toward the normal, i. e., there is a tendency of the shell to glance. The result is that the rear of the projectile is forced sidewise and it smashes with great force against the face of the armor. The rear portion of the body, if fitted with a solid base-plug, cannot yield elastically and is crushed as if by a forging hammer. When the projectile is provided with my flexible base-plug, however, the base yields elastically to the forces acting and thereby absorbs a large part of these forces and diminishes the crushing force acting on the projectile body, thus insuring that the projectile will be preserved intact.

When the projectile strikes at angles between approximately 45° and 60°, the projectile may penetrate or may strike a glancing blow and rebound. One of the possible conditions is that illustrated in Fig. 6, wherein the point of the projectile may not at first "bite" or penetrate, but as the plate, if thin, is deformed, the bending of the plate increases the angle between the face of the plate and the longitudinal axis of the pro-

jectile, causing the projectile to bite. There is, however, a simultaneous tendency for the projectile's longitudinal axis to be deflected toward parallelism with the plate and for

5 the projectile to glance. The effect of these influences cannot be predicted, but it will be seen that the desirability of a flexible base-plug is substantially as great as in the cases previously illustrated.

10 If my improved projectile and base-plug be deformed, due to the action of forces described above, they will be deformed elastically and in the same degree, and the connection between the base-plug and the body 15 will be preserved. Therefore, as long as a projectile remains intact, the generation of a pressure inside of the projectile cavity will expand obturating lip 24 into engagement with the projectile body, sealing the explosive chamber so that the full expansive force 20 of the explosive gases may be exerted against the walls of the projectile and the face of the base-plug. The pressure of the gases on the inner face 13 and the resistance 25 of screw-threads 12 react in such a manner as to expand the perimeter of plug 11, thereby insuring against the escape of the gas rearwardly past said plug and insuring complete fragmentation of the projectile.

30 It will be perceived that I have provided a projectile of superior ability as regards penetration of armor plate at oblique impact and at the same time have provided a projectile which will meet the most exacting 35 requirements as to fragmentation.

It will be noted that, while my improved projectile comprises a base-plug which yields to side stresses, such as have been described, the form and construction of said 40 plug is such that its ability to withstand the longitudinal stresses generated by the explosion of the fragmenting charge is fully the equal of, if not superior to, the solid plugs heretofore used.

45 While several embodiments of the inventive idea have been heretofore described and illustrated in detail, it is to be understood that the invention is not limited thereto, and that the inventive idea may be embodied 50 in various mechanical expressions within the limits of the appended claims.

What is claimed is:—

1. A projectile comprising a body portion having a cavity therein, and flexible means 55 for closing said cavity for rigidly resisting longitudinal stresses, and for yieldingly resisting the radial stresses encountered when the projectile penetrates its objective.

2. An armor-piercing projectile comprising 60 a body portion having a cavity therein and a flexible plug for closing said cavity.

3. A projectile comprising, in combination 65 with a body portion, a flexible base plug having an inner face of truncated conical shape, said plug being adapted to rigidly re-

sist longitudinal stresses and to yieldingly resist the radial stresses developed when the projectile penetrates or strikes its objective at an oblique angle.

4. A projectile comprising, in combination 70 with a body portion, a base plug having an annular obturating groove in the front face thereof and adapted to rigidly resist longitudinal stresses and to yieldingly resist the radial stresses developed when said projectile penetrates or strikes its objective at an 75 oblique angle.

5. A projectile comprising, in combination 80 with a body portion, a base plug having a concentric opening therein, the forward portion of said opening being of relatively small diameter, and the after portion thereof being of relatively large diameter, said plug being so formed as to rigidly resist longitudinal stresses and yielding resist radial stresses 85 encountered when the projectile strikes its objective.

6. An armor-piercing projectile comprising, in combination with a body portion having a cavity for explosives therein, flexible 90 means for insuring fragmentation when the projectile penetrates at oblique angles.

7. An armor-piercing projectile comprising, in combination with a body portion having a cavity for explosives therein, a flexible 95 base-plug for increasing penetration when the projectile strikes its objective at an oblique angle.

8. A flexible base-plug for armor-piercing projectiles, having an obturating groove in 100 the front face thereof, said face being of truncated conical shape and extending beyond the front periphery of said plug.

9. Flexible means for sealing the rear end 105 of the explosive cavity of an armor-piercing projectile and adapted to maintain said seal during the passage of said projectile through armor-plate at oblique angles.

10. A deformable base-plug for a projectile having the periphery thereof threaded, 110 an axial cavity of varying diameters extending therethrough, and a forward face of truncated conical shape projecting beyond the forward end of said threaded portion.

11. A projectile comprising, in combination 115 with the body portion, a base-plug recessed at its axis to render the same elastic.

12. A projectile comprising, in combination 120 with the body portion, a deformable base-plug adapted to yield to lateral stresses, rigidly resist longitudinal stresses and maintain a gas-tight seal with said body portion when the projectile strikes its objective.

13. A deformable base-plug for an armor-piercing projectile adapted to conform to the 125 deformations of the body portion of said projectile during the piercing of an objective by said projectile.

14. A deformable base plug for an armor-piercing projectile adapted to yield to lateral 130

stresses and to rigidly resist longitudinal stresses.

15. An armor-piercing projectile comprising in combination with a body portion having a cavity for explosive therein, a flexible base-plug adapted to cooperate with said body in yielding elastically to the side

stresses set up in said body portion when the projectile strikes its objective at an oblique angle.

In testimony whereof I have signed this specification.

HARRY J. NICHOLS.
